UNITED STATES PATENT OFFICE

DANIEL AMBROSE BRADLEY, OF LONDON, ENGLAND, ASSIGNOR TO BOABANDS LIMITED, OF LONDON, ENGLAND, A BRITISH COMPANY

TIGHTENING AND SEALING DEVICE

Application filed November 13, 1931, Serial No. 574,900, and in Great Britain November 20, 1930.

This invention is for improvements in or relating to a tightening device for use in tightening a band, strap or the like, that is looped about a box or package and is to have its ends secured together by a clip or fastener to which primarily one end portion of the band is attached, which device is of the type comprising tensioning means, for example a pawl tensioning device, to which the second end portion of the band extending across the clip is to be attached, and a support for the tensioning means having an abutment arranged to take up the reaction due to the pull of the tensioning means on the band and hold the clip against movement of the band whilst the clip is being secured in position on the band.

The present invention has for one of its objects to provide an improved construction of tightening and sealing device of the type described that readily permits a clip or fastener attached to one end of the band to have the second end secured thereto whilst the band is held under tension closely around the box or package, and whilst the clip lies flat against a side of the box or package.

According to the invention a tightening device of the type described is characterized in that a face of the support which is to lie against a side of the box or package has in it a recess for receiving the clip in a position in which it lies close to said side of the box or package and parallel with and close to the said second end portion of the band. Owing to this construction of the device the band is strapped tightly around the box or package with the clip in that position in which it is to remain after the removal of the tightening device, so that the removal of the tightening device does not slacken the tightened band. The clip or fastener is preferably of the type wherein a plate forming its body has lugs arranged to be folded down on the band and clamp it securely on the plate. Several forms of such a fastener are described in the co-pending patent application Serial No. 574,901 on which Patent No. 1,855,007 has been granted.

According to a feature of the invention the said abutment is constituted by an end wall of the recess lying transversely of the band.

According to another feature of the invention the support is arranged to remain stationary on the box or package, and the tensioning means is so mounted on the support that whilst maintaining the tension on the band it can swing along a semi-circular path whereof the axis is at the clip and lies across the width of the band.

The support for the tensioning means may consist of one or more arcuate guides for it spaced apart. These guides may constitute a bearing for the tensioning means carried by a lever arm arranged to swing about them.

According to another feature of the invention positioning means for the box or package is arranged on the support for locating the clip carried by the box or package against the said abutment.

The invention also provides a tensioning device as set forth above in combination with sealing means mounted on the support for closing the clip on the band whilst the latter is under tension.

Conveniently the sealing means comprises a plunger movable in a hole in the support towards and away from the clip, and a lever pivoted on the support and arranged to reciprocate the plunger.

According to a further feature of the invention the sealing means comprises a plunger movable in a hole in the support towards and away from the clip, and a lever pivoted on the support and arranged to reciprocate the plunger.

The sealing means may have actuating means arranged to be operated by the tensioning means, or by means, for example a cam, carried thereby, as it is being swung on said support and approaches its said second end position.

According to a further feature of the invention a cutting device is arranged to sever the second end portion of the band, for example automatically, when the tensioning means is near or at its second end.

position. This cutting device may be arranged to be actuated substantially simultaneously with the sealing means either by the tensioning means or independently thereof.

Other features of the invention will be described hereinafter and pointed out in the claims.

Several embodiments of the invention are 10 diagrammatically illustrated by way of example in the accompanying drawings, wherein:—

Figure 1 is a side elevation showing one 15 form of tightening device according to the invention, comprising sealing means and a cutting device for the band;

Figure 2 is a vertical section taken on the bent line 2—2 in Figure 1;

Figure 3 is a plan view of the tightening 20 device as shown in full lines in Figure 1;

Figure 4 is a plan view of the tightening device as shown in Figure 1 when the tightening means is in the position shown in broken lines, and

25 Figure 5 is a diagrammatic plan view illustrating the operation of the sealing means;

Figure 6 is a side elevation of another 30 form of tightening device according to the invention, and

Figure 7 is a plan view thereof, part of the tightening means being shown broken away for the sake of clearness;

Figure 8 is a side elevation showing another 35 form of tightening device according to the invention;

Figure 9 is a plan view thereof;

Figure 10 is a vertical section taken on the line 10—10 in Figure 9;

40 Figure 11 is a plan view of the sealing means, and

Figure 12 is a horizontal section through 45 part of the sealing means taken on the line 12—12 in Figure 10.

Like reference characters designate like or similar parts in all the views.

Referring first to Figures 1 to 5, a circular support designated generally 15 for the tensioning means aforesaid comprises 50 two annular walls 16, 17 spaced apart in parallel relation to provide between them at one side of the support a deep gap 18 extending inwards to a plane lying substantially along a diameter of the support. At 55 the opposite side of the support, herein-after referred to as the base portion of the support, the walls 16, 17 are secured firmly together, and have fashioned in them a relatively wide positioning slot 20 which is 60 situated at right angles to said plane and extends from the bottom of the gap 18 to the periphery of the base portion. This slot 20 serves to receive an end or side of the box or package carrying the band to one 65 end of which is attached the clip lying flat

against the end or side of the box or package. In Figure 1 the package is indicated at 22 and the band at 23 in broken lines, while the Figure 5 shows the same in full lines and the clip 24.

At the bottom of the slot 20 there is a recess 26 for receiving the clip 24. This recess is formed by two parts 27, 28, (see Figure 2), one in each of two middle portions 29, 30 of the side walls of the support. Two screws 32, 33, one in each face 27, 28, adjustably secure in position two blocks 34, 35 which are adjustable towards and away from one another for accommodating clips of different width, and have each a shoulder 70 providing an abutment 36 for the clip.

Each wall 16, 17 has in its inner side face 75 an annular groove 38, 39, respectively, and an arcuate shoe 40 having two pivot pins 42, 43, each carrying an antifriction roller 44, 45, respectively, is mounted to travel around the support from one side to the other, with the rollers running in the grooves 38, 39. This shoe 40 has a radial 80 bracket 48 carrying a spindle 49, whereof one end lies in the plane of said gap 18 and has fixed on it a boss 50 having a cruciform slot 51 for receiving the second end portion of the band. This spindle 49 is part of pawl and ratchet tensioning means 85 54, 55, 56 comprising an arm 57 that is carried by the spindle 49 and, when rocked about the latter, serves to tighten the band about the package. A handle member 59 secured to the shoe 40 serves to carry the 90 entire tightening device.

Each of the walls 16, 17 has on its outer side near the middle a boss 60 having a hole 61 slanting downwards towards the said recess 26 for receiving the clip. Two spring-controlled plungers 64 are provided, one 95 62 slidable in each hole, for working on and closing the clip from opposite sides thereof. Each plunger is guided by a pin 66 in a slot 68 in the boss, to which pin 66 one end of a compression spring 70 is connected, the other end thereof being anchored to the support 15. Each boss carries a lever 72 having at one end a spherical head 73 bearing on a plunger 64, and at its other end an anti-friction roller 74. When these levers 72 are rocked by a wedge-shaped cam 75 of the shoe 40 co-acting with the rollers 74 as described hereinafter the plungers 64 are driven inwards, as indicated in Figure 100 110 115 9695 9700 9705 9

terminates adjacent to that end portion. The opposite face 78 of the positioning slot 20 which constitutes a channel guide-way for the box or package is preferably provided with clamping means 80 for clamping the box or package in position against the guide face 76. As illustrated in Figures 1 and 2, the clamping means is in the form of a clamping plate 80 arranged to be reciprocated by an eccentric 82 on a spindle 83 that is journalled in the base of the support and carries a handle member 84.

The shoe 40 of the tensioning means carries at its forward end one blade 86 of a cutting device 86, 87, whereof the co-operating blade 87 is fixedly carried by the support at the diametral plane aforesaid at the bottom of the gap 18.

The described tensioning device is operated as follows:—A clip 24 as described in the said copending patent application has attached to it one end portion of a band 23 which is placed around the package and has its second end portion lying across the clip underneath an anchor 240 and between two lugs thereof, and extending upwards. The package is then placed into the slot 20 so that the clip lies in the recess 26 and the second end portion of the band extends upwards in the slot 18 and is placed in the cruciform slot 51 of the tensioning means situated in the position shown in full lines in Figure 1. By oscillating the lever arm 57 the tensioning means is actuated and the band tightened around the package, the reaction on the clip being taken up by the abutment 36. By swinging the shoe 40 around to the other side of the support into the position shown in broken lines in Figure 1 the second end portion of the band will be folded backwards on itself over the said anchor and will lie across the cutting edge of the blades 87, as indicated by a dot and dash line. When the shoe 40 passes the levers 72 they are rocked apart by the cam 75, whereby the plungers 64 are driven inwards to close the lugs of the clip on the folded second end portion of the band. Immediately afterwards, on moving the shoe 40 further in the same direction, the blades 86, 87 sever the band at a point away from the clip a distance approximately equal to the radius of the arcuate support. The package encircled by the sealed band can be removed from the apparatus, and the free end of the band extending beyond the clip can be shortened by hand, if desired.

Referring now to Figures 6 and 7, the support 15 and pawl and ratchet tensioning means 54, 55 and 56 of this modified tensioning device are substantially the same as those of the device shown in Figures 1 to 4, but the shoe 40 has a cam 90 rotatably mounted on it instead of integral therewith. The levers 72 co-operating at one end with

the plungers 64 carry at their other ends anti-friction rollers 74 which, when the shoe 40 is in the position shown in Figures 6 and 7, can be forced apart to operate the plungers 64 by rotating the cam 90 by means of its handle member 92. When the levers 72 are rocked by the cam 90 an arm 94 of a bell-crank lever 94, 95 that is fulcrumed on the support at 96 is also rocked, so that the arm 95, which carries a movable cutter blade 186 that co-operates with a fixed cutter blade 87, operates to sever the second end portion of the band after the clip has been secured on the band. In this construction the clamping plate 80 is carried by a screw 98 movable in the jaw of the support opposite to the face 76. If desired, the lever 94, 95 can be dispensed with, and the cutting device 186, 87 may be arranged as described with reference to Figures 1 to 4.

Referring now to Figures 8 to 12 a support 100 of L-shape is provided with the guide face 76 aforesaid for the package 22, whilst its face 102 at right angles thereto has said recess 226 for receiving a clip. This construction of support obviates the use of a slot 20 which limits the device to use with packages of certain sizes, and enables the device to be placed with the face 76 horizontally on the top face of packages of any size and with the face 102 bearing against a vertical side of the package.

The tensioning means comprising the shoe 40 is similar to that described above with reference to Figures 1 to 4, but a stop 104 is fixed on the shoe 40 in such a position that the handle member 57 can bear against it and swing the tensioning means from its starting position shown in full lines in Figure 8 round to the other side of the arcuate guide 16 to its second end position indicated in broken lines in Figure 8. In this position the handle member 57 can rest on a stop 106 fixed at the end of the longer limb of the support. The ratchet wheel 154 of the tensioning means is co-axial with a spur gear wheel 108 which meshes with a gear wheel 109 fast on the spindle of the slotted boss 50.

In this construction the sealing means comprises a pair of mutilated rollers 110, 111 carried each by a vertical pivot pin 112, 113, respectively, journalled in the support at opposite sides of the recess 226, and in such a position that a flat face 114 on each roller serves to close the clip on the band, as indicated in Figure 12, when the rollers are rotated in opposite direction, as described hereinafter. These rollers are provided respectively with a co-axial spur gear wheel 116, 117 which mesh respectively with larger gear wheels 118, 119, which are both driven simultaneously in opposite directions by a toothed segment 120 formed or provided on an operating arm 121 pivotally

mounted at 122 on the support. This arm 121 constitutes the lower prong of a forked actuating member 124 whereof the upper prong 123, also pivoted at 122, lies above the toothed segment 120 and is pivotally connected at its end to one end of a connecting rod 126 which has its other end connected to one arm 194 of a bell-crank lever 194, 195, whereof the arm 195 carries a blade 186. A spring 128 anchored at one end to a handle member 130 on the support has its other end attached to the prong 123 and tends to hold the sealing means and cutting device in the position shown in Figures 8 and 9. After the tensioning means has been swung into its upper position shown in broken lines in Figure 8 and the actuating member 124 is moved against the action of its spring 128, the sealing means and cutting device are operated in unison, by turning the hand lever 124 about its pivot 122 in a counter-clockwise direction as viewed in Figure 9. This movement of the lever 124 causes rotation of the gear wheels 118, 119 which operate the sealing rollers 110, 111 by means of their pinions 116, 117, and at the end of the sealing operation, the lever arm 195 carrying the movable blade 186 has moved angularly so far, owing to its connection by the rod 126 with the lever 124, that the movable blade 186 co-operates with the fixed blade 87, so that the cutting device does not sever the band until the clip has been fastened upon it.

In each of the constructions described above, the tensioning means is so mounted on the support that whilst maintaining the tension on the band it can swing through 180° or more along a semi-circular path whereof the axis is at the clip and lies across the width of the band.

It will be appreciated that in each of the constructions described above an end portion of the band extends across one of the cutter blades when the band has been tightened and folded on itself, and that in the construction shown in Figures 8 to 12 the band is severed close to the clip.

Various modifications may be made in the details of construction described above without departing from the scope of the invention.

I claim:

1. A tightening device of the character described comprising in combination a support having a face which is to lie against a side of a package to be encircled by a band, in which face is a recess for receiving a clip in a position in which it lies close to said side of the package, which clip has an anchor over which the band may be bent backwards, and to which clip one end portion of the band is to be preliminarily attached, a tensioning means which is mounted on the support, and to which the second end portion

of the band extending across the clip is to be attached, which tensioning means is arranged to swing, whilst maintaining the tension on the band, along a semi-circular path whereof the axis is at the anchor of the clip and lies across the band.

2. A tightening device of the character described comprising in combination a support having a face which is to lie against a side of a package to be encircled by a band, in which face is a recess for receiving a clip in a position in which it lies close to said side of the package, which clip has an anchor over which the band may be bent backwards, and to which clip one end portion of the band is to be preliminarily attached, a tensioning means which is mounted on the support, and to which the second end portion of the band extending across the clip is to be attached, and an abutment on said support arranged to take up the reaction due to the pull of the tensioning means on the band and hold the clip against movement by the band whilst the clip is being secured in position on the band, which support comprises at least one arcuate guide along which the tensioning means is arranged to swing about an axis that is situated at the anchor of the clip and lies across the band.

3. A tightening device of the character described comprising in combination a support having a face which is to lie against a side of a package to be encircled by a band, in which face is a recess for receiving a clip in a position in which it lies close to said side of the package, which clip has an anchor over which the band may be bent backwards, and to which clip one end portion of the band is to be preliminarily attached, a tensioning means which is mounted on the support, and to which the second end portion of the band extending across the clip is to be attached, and an abutment on said support arranged to take up the reaction due to the pull of the tensioning means on the band and hold the clip against movement by the band whilst the clip is being secured in position on the band, which support comprises two parallel arcuate guide members spaced apart to accommodate the second end portion of the band between them, along which guide members the tensioning means is arranged to swing about an axis that is situated at the anchor of the clip and lies across the band.

4. A tightening device of the character described comprising in combination a support having a face which is to lie against a side of a package to be encircled by a band, in which face is a recess for receiving a clip in a position in which it lies close to said side of the package, which clip has an anchor over which the band may be bent backwards, and to which clip one end portion of the band is to be preliminarily attached, a ten-

sioning means which is mounted on the support, and to which the second end portion of the band extending across the clip is to be attached, and an abutment on said support arranged to take up the reaction due to the pull of the tensioning means on the band and hold the clip against movement by the band whilst the clip is being secured in position on the band, which support comprises two parallel arcuate guide members spaced apart to accommodate the second end portion of the band between them, along which guide members the tensioning means is arranged to swing about an axis that is situated at the anchor of the clip and lies across the band, which recess is formed in two parts, one in each of said guide members.

5. The combination with a support having a recess for receiving a clip to which one end portion of the band is to be attached, a tensioning means which is mounted on the support and to which the second end portion of the band extending across the clip is to be attached, and an abutment on said support arranged to take up the reaction due to the pull of the tensioning means on the band, of sealing means mounted on the support for closing the clip on the band while the latter is under tension, which sealing means comprises a pair of mutilated rollers geared together to rotate in opposite directions and arranged to press and close the clip on the band.

6. The combination with a support having a recess for receiving a clip to which one end portion of the band is to be attached, a tensioning means which is mounted on the support and to which the second end portion of the band extending across the clip is to be attached, and an abutment on said support arranged to take up the reaction due to the pull of the tensioning means on the band, of sealing means mounted on the support for closing the clip on the band while the latter is under tension, and a cutting device arranged to sever the second end portion of the band when the clip is secured on the band, which sealing means and cutting device have an actuating member common to them both.

7. The combination with a support having a recess for receiving a clip to which one end portion of the band is to be attached, a tensioning means which is mounted on the support and to which the second end portion of the band extending across the clip is to be attached, and an abutment on said support arranged to take up the reaction due to the pull of the tensioning means on the band, of sealing means mounted on the support for closing the clip on the band while the latter is under tension, and a cutting device arranged to sever the second end portion of the band when the clip is secured on the band, an actuating member

common to said sealing means and said cutting device, toothed wheel gearing operatively connecting the actuating member to said sealing means, and a connecting rod operatively connecting the actuating member to said cutting device.

In testimony whereof I affix my signature.

DANIEL AMBROSE BRADLEY.
